UNITED STATES PATENT OFFICE.

CHILDE HAROLD WILLS, OF MARYSVILLE, MICHIGAN.

OIL-FEEDING MEANS.

Application filed November 12, 1920. Serial No. 423,681.

To all whom it may concern:

Be it known that I, CHILDE HAROLD WILLS, a citizen of the United States, residing at Marysville, in the county of St. Clair and 5 State of Michigan, have invented certain new and useful Improvements in Oil-Feeding Means, of which the following is a specification.

This invention relates to oil feeding means. 10 The invention is of especial utility in connection with the lubrication of the cams of the cam shaft of a hydrocarbon motor from the hollow interior of the shaft, and also has particular advantages in automobile motors in which there is a change of level due 15 to differences in grade.

The principal object of the invention is to provide for an equal distribution of oil from a hollow body to a plurality of parts to be 20 lubricated at a uniform rate of feed, and in sufficient volume to provide proper lubrication.

Another object of the invention is to enable oil to be fed by pressure directly to the 25 exterior faces of the valve operating cams of a hydrocarbon motor.

Another object of the invention is to insure a sufficient feed of oil to all the cams of an automobile motor when the vehicle is 30 ascending or descending a grade.

With these objects and others in view, the invention is embodied in preferable form in the construction hereinafter described and illustrated in the accompanying drawing, in 35 which—

Figure 1 is a longitudinal central cross-section of the cam shaft of a hydrocarbon motor and associated parts, and

Fig. 2 a cross-section taken through one 40 of the cams.

In the lubrication of the cams of the cam shaft the oil is fed to the interior of the shaft, and passes through ducts therein to the outer surfaces of the cams. There is a 45 tendency in the cam shaft to throw the oil fed thereto toward the front of the shaft, thus causing an undue supply of oil to the front cams with a consequently diminished supply to the rear cams. This invention 50 prevents the excessive feed to the front cams, and also prevents an excessive feed to the rear cams when the automobile is ascending a hill.

The invention consists of a tube or a plu-

rality of tubes mounted within the hollow 55 cam shaft or similar body, and having a duct therethrough of less diameter than the total diameter of the channels leading through the cams or other parts to be supplied with oil from said tube, and into which 60 tube the oil is conducted from the source of oil supply whereby the oil feed will be restricted and metered by the hole in the tube, and thus the feed regulated so as to maintain a uniform supply to all the cams and 65 also a sufficient amount of oil for each cam at all times.

Referring to the drawings, 1 is a hollow cam shaft, and 2 cams carried thereby. These cams have ducts 3 leading through the 70 same to the outer contact faces thereof. A hole 4 admits oil under pressure to the interior of the hollow cam shaft which forms a part of the oiling system. The pressure is supplied by a pump 5 shown diagrammatically. The invention is shown as applied to a cam shaft for the valves 6 of the four cylinders of one set of cylinders of a V-type, eight cylinder motor. Within the hollow cam shaft are mounted two identical 75 tubes 7, one located opposite each of the two sets of four cams at the forward and rear parts of the cam shaft. Each of these tubes is expanded at each end thereof at 8 so as to closely fit the wall of the cam shaft to 80 thereby cause the oil entering the center of the shaft to pass into the tubes. Between these expanded plug ends of each tube the body of the latter is separated from the wall 85 of the cam shaft, providing an annular space 90 9 surrounding the four cams to which the tube corresponds. The oil is forced into and through the tubes by the oil pressure. 10 is a small duct formed in the wall of the tube 95 and leading to the annular space 9. The diameter of this duct is less than the total 100 diameters of the ducts or channels 3 leading through the cams. The oil is thus restricted and metered by this single duct, and owing to its relatively small diameter the tube will 105 always be sufficiently supplied with oil to furnish proper quantities to all the cams. This duct is preferably of the same diameter as each of the ducts through the cams. This metering of the oil by means of the tube 110 also renders it possible to maintain sufficient pressure of the oil in the direct feed of oil to the cams from the pressure oil system as

distinguished from those arrangements in which the cams are lubricated by splash or drip feed.

Having thus described my invention, what I claim is:

1. In combination with a hollow member, a plurality of parts to be lubricated having ducts communicating with said hollow member, means to admit oil to said hollow member, and means in said hollow member interposed between the entrance of oil and the said ducts having restricted passage means for the oil of less diameter than the total diametrical area of said ducts.
  2. In combination with a hollow shaft, a series of members to be lubricated having ducts communicating with the interior of said shaft, a tube mounted in said shaft to receive lubricant supplied to the shaft, said tube being spaced from the shaft opposite said ducts, and having oil passage means therethrough leading to said space.
  3. In combination with a hollow shaft and parts having ducts communicating with the interior of said shaft for lubrication of said parts, a tube in said shaft adapted to receive the oil supplied to the latter, said tube having portions opposite said ducts spaced from the hollow shaft, and having an oil passage therethrough adapted to establish communication between the tube and said ducts.
  4. In combination with a hollow shaft and parts having ducts communicating with the interior of the shaft for lubrication, a tube in said shaft adapted to receive oil admitted to the shaft and spaced from the wall of the latter, said tube having a single opening therethrough to admit oil from the tube to said space.
  5. In combination with a hollow shaft and parts having ducts communicating with the interior of said shaft for lubrication thereof, a tube in said shaft closely fitting said
- shaft at each end of the tube and spaced on the shaft intermediate said ends, means for admitting oil to said shaft and tube, and said tube having oil passage means therethrough leading to said space, of less diameter than the total diameters of said ducts.
6. In combination with a hollow shaft and parts having ducts communicating with the interior of said shaft for lubrication, means for admitting oil to said shaft, a tube in said shaft open at its ends and closely fitting at said ends the wall of the shaft, said tube being spaced from the wall of the shaft intermediate said ends and having an opening therethrough communicating with said space, said opening being of approximately the same diameter as one of said ducts.
7. In a hydrocarbon motor, the combination with a hollow cam shaft, of pressure oil feed means communicating with said shaft, cams on said shaft, ducts leading from the interior of said shaft through said cams to the faces of the latter, and conduit means in the shaft through which the oil must pass to the ducts having restricted passageway means therein of less diameter than the total diametrical area of the cam ducts.
8. In a hydrocarbon motor, the combination of a hollow cam shaft, two series of cams thereon, means for admitting oil to said shaft between said two series of cams, a tube in said shaft at each side of said oil admitting opening having its ends extending beyond said cams and closely fitting the wall of the shaft and spaced from said wall intermediate said ends, said cams having ducts communicating with said space and leading to the exterior faces of the cams, and an oil restricting opening leading through said tube to said space.
- Signed at Marysville, Michigan, this 19th day of October, 1920.
- CHILDE HAROLD WILLS.
